UNITED STATES PATENT OFFICE.

OTIS A. MYGATT, OF NEW YORK, N. Y.

DESIGN FOR AN INCANDESCENT-ELECTRIC-LAMP BULB.

No. 38,005.

Specification for Design.

Patented May 8, 1906.

Application filed January 29, 1904. Serial No. 191,222. Term of patent 14 years.

To all whom it may concern:

Be it known that I, OTIS A. MYGATT, a citizen of the United States, residing at New York, in the county of New York and State of New York, have invented a new, original, and ornamental Design for an Incandescent-Electric-Lamp Bulb, of which the following is a specification.

The design is embodied in an electric-lamp bulb of glass.

Figure 1 is a side elevation of an electric-lamp bulb, showing the design so far as the same can be illustrated in a line-drawing. Fig. 2 is a bottom plan of the same.

The lamp-bulb is of substantially spherical form projecting from a cylindrical supporting-stem. The upper portion of the bulb is covered with reflecting-prisms integral

with the body and projecting as lunes. The prisms terminate in rounded ends at about the largest diameter of the bulb. These prisms present an iridescent appearance. The lower part of the bulb below the prisms is of frosted glass, giving a pearl-like appearance to this portion of the bulb.

What I claim is—

The ornamental design for a spherical lamp-bulb, having the upper hemisphere covered with reflecting-prisms arranged as lunes, and the lower hemisphere frosted, as shown and described.

OTIS A. MYGATT
